CLAIM

The ornamental design for a bottle, as shown and described.

DESCRIPTION

FIG. 1 is an isometric view of a front, top, and left side of an ornamental design for a bottle;

FIG. 2 is a front elevational view of the bottle of FIG. 1;

FIG. 3 is a rear elevational view of the bottle of FIG. 1;

FIG. 4 is a right side elevational view of the bottle of FIG. 1, the left side elevational view being a mirror image thereof;

FIG. 5 is a top plan view of the bottle of FIG. 1; and,

FIG. 6 is a bottom plan view of the bottle of FIG. 1.

It is understood that the bounds of the claimed design are represented by peripheral portions of the shade lines in FIGS. 1-6. The dash-dash-dash broken lines are for the purpose of illustrating environmental structure and form no part of the claimed design.
